UNITED STATES PATENT OFFICE.

WILLIAM C. CODMAN, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A HANDLE FOR SPOONS, FORKS, OR SIMILAR ARTICLES.

● 44,193.

Specification for Design.

Patented June 17, 1913.

Application filed April 21, 1913. Serial No. 762,735. Term of patent 14 years.

To all whom it may concern:

Be it known that I, WILLIAM C. CODMAN, a subject of the King of Great Britain, residing at Providence, in the county of Providence and State of Rhode Island, have invented a new, original, and ornamental Design for Handles for Spoons, Forks, or Similar Articles, reference being had to the accompanying drawings, in which—

Figure 1 is a view of the obverse side of the handle, showing my design. Fig. 2 is an enlarged detail perspective view.

I claim—

The ornamental design for a handle for spoons, forks or similar articles.

WILLIAM C. CODMAN.

Witnesses:

ADA E. HAGERTY,
J. A. MILLER.
